UNITED STATES PATENT OFFICE

ROBERT A. CRAWFORD, OF CHAMBERLAIN, SOUTH DAKOTA

HUMIDIFIER

Application filed February 8, 1928. Serial No. 252,853.

This invention relates to humidifying attachments for radiators, and it has, for its object, to provide highly efficient apparatus, adapted to be mounted in connection with the ordinary house heating hot water or steam radiators, and constructed in such manner as to evaporate a very much greater amount of water than has been possible with known devices of this sort.

10 Further objects and advantages of the invention will be set forth in the detailed description which follows:

In the accompanying drawings,

Fig. 1 is a side elevation of a radiator, having the apparatus of the present invention applied thereto.

Fig. 2 is a vertical, sectional view therethrough, with the radiator in elevation.

Fig. 3 is a plan view of the top of the radiator, and the water pan, with the cover of the radiator removed, and with one set of the wicks removed.

Fig. 4 is a perspective view of a pair of the wicks, hereinafter described.

25 Fig. 5 is a transverse sectional view through the water pan and radiator, showing the wicks in position.

Fig. 6 is a plan view of the drip pan.

Figure 7 is an end elevation of the drip pan. 30 Like numerals designate corresponding parts throughout the several figures of the drawing.

In the drawing, 5 designates a conventional type of heating radiator, such as is commonly employed in homes, and other buildings, for the purpose of heating the same.

It is a well known fact that a certain degree of moisture in the air, in a dwelling, is highly desirable; not only for the health and comfort of the occupants of the building, but for the most economical results in heating.

Cold air is able to absorb very little moisture, and cold air coming in from the outside, even though it were saturated with moisture when cold, becomes exceeding dry when warm.

This dry air is then able to absorb a very large amount of moisture, and it is the purpose of the present invention to supply this moisture in a most efficient way. It is well known to heating engineers that a residence is much

more comfortable to human beings at 68 degrees, when the air is moist, than it is at 70 degrees, or over, when the air is dry. That is to say, the air feels warmer at a given temperature if moist, than it does when it is dry.

Furthermore, the normal condition of the human skin is a moist condition, and it follows that a moist atmosphere tends to keep the skin in its normal condition, and consequently in its most helpful and comfortable condition.

Many attempts have been made to provide water evaporating attachments for heating radiators. However, all of the devices of this sort, with which I am familiar, have had but a very limited evaporative capacity. This has usually been due to the fact that they expose but a relatively small area of surface of water to the heat of the radiator. It is not sufficient that an apparatus of this sort exposes a large volume of water to the heat of the radiator. Volume is not controlling.

It is the surface that is exposed for evaporation that determines how much water will be evaporated in a given time, and at a given temperature of the radiator. Therefore, I have devised an apparatus which utilizes all of the spaces between the sections of the radiator, substantially throughout the entire height of the radiator, to bring about the evaporative effect, and, as a result, I have produced an apparatus which will evaporate a very large quantity of water in a relatively short time.

Further, I have devised an apparatus which will automatically control the amount of water delivered thereto, in accordance with the moisture content of the air in the room.

To accomplish this result I mount upon the top of the radiator a pan 6, to which water is supplied from a water supply pipe 7. A conventional type of float valve 8 serves to maintain a predetermined level in the pan 6. If, for any reason, this float valve should fail to operate the water may escape through an overflow pipe 9 to the sewer 10. A circuit closing hygrometer 11 acts to control an electrically operated valve 12, in the water supply line 7, and when the humidity of the air in the room has reached the desired degree,

said hygrometer acts to shut off the water, by the operation of valve 12, so that no more water will flow to the pan 6, until the moisture content has been lowered beyond the point for which the hygrometer is set; at which time the valve will again be automatically opened, and the water will flow to pan 6. Circuit controlling hygrometer have acquired a distinct status in the art, and are widely used in connection with lumber drying kilns, and like apparatus, and, consequently, further description of this element is not necessary.

The pan 6 is divided into three longitudinal channels, 6^a, 6^b, 6^c, and two cross end channels 6^d, 6^e, which connect the longitudinal channels. This leaves two open spaces 14 and 15 through the pan, which overlie the radiator sections. Parallel wires or rods 16 and 17 are connected at their ends by the cross rods 18 and these rods constitute wick carriers. These wick carriers are secured in any desired way upon the pan 6, as for example, by thumb screws 19, and they extend longitudinally above and overlie the spaces 14 and 15. Each longitudinal wire of each wick carrier has a plurality of vertically disposed elongated wicks, depending therefrom. These wicks consist of the crossed wire frames 20, which carry webs of suitable wick material 21, such as a porous cloth, for example. The crossed wire frames 20 are secured to the longitudinally extending rods of the wick carriers, and at their point of juncture, tufts of water conductive material 22 are disposed. These tufts may consist of small pieces of sponge, or they may consist of extended portions of the cloth 21, brought to tufted formation.

These vertically disposed elongated wicks 40 project downwardly into the spaces between the radiator sections. Transversely, and horizontally disposed wicks 23 extend across and are connected to the tufts 22, and have their outer ends downturned into the channels 6^a, 6^b, or 6^c, 6^d, as the case may be. These cross wicks serve to conduct the water from these channels to the tufts 22 and thence to the vertical wicks, where it is fed downwardly, both by capillarity and by gravity. The 50 distance that the water must be conducted wholly under the influence of capillarity is very short, and the fact that the remainder of the feed of the water is under the influence of gravity, as well as capillarity, results in a very efficient feeding of the water to the vertical wicks. Since these vertical wicks are exposed to the heat of all of the radiator sections throughout substantially the entire height of the latter, it follows that the effective evaporative area is very great, and, consequently, the amount of water that may be evaporated by this arrangement is correspondingly large.

A drip pan 24 is disposed beneath the radiator and has a channel 25 formed in its bot-

tom, which is in communication with the sewer 10, through a connection 26. This pan serves to receive any drip that may take place from the lower ends of the vertical wicks. I contemplate employing a cover 27 to cover the radiator and pan 6, and this cover may be made throughout, or to any desired extent, of ornamental grill work, so that an efficient circulation of the air therethrough may be maintained.

It is to be understood that the invention is not limited to the precise construction set forth, nor to the particular shape of the parts illustrated, because these will be varied as the different types of radiators require. Consequently, I wish to make it clear that the invention includes within its purview whatever changes fairly come within either the spirit or the terms of the appended claims.

Having described my invention, what I claim is:

1. In combination, a radiator comprising a plurality of spaced sections, a water pan, shaped and dimensioned to rest upon and extend longitudinally along the top of the radiator throughout substantially the length thereof, elongated wicks extending downwardly from said pan, shaped to lie between the radiator sections and transverse wicks connected to the tops of the first named wicks and having their terminal ends disposed in the water in the pan, said transverse wicks serving to feed the water from the pan to the vertical wicks.

2. The combination with a radiator, comprising a plurality of sections spaced from each other, of a water supply pan mounted thereon and extending substantially the full length thereof, vertical wicks suspended from said pan and lying between the radiator sections, means for feeding water from the pan to said vertical wicks, and a housing covering the pan and the upper portion of the radiator, said housing having a foraminous side, an open bottom and a closed top.

3. The combination with a radiator comprising a plurality of spaced sections, of an elongated pan supported upon the top of the radiator and overlapping substantially all of said sections, a plurality of vertical wicks lying between the radiator sections and inwardly of the outer edges thereof, and extending downwardly between said radiator sections throughout the major portion of the height of said sections, and means for feeding water to said wicks by capillarity from said pan.

4. A structure as recited in claim 3, in combination with a housing disposed over said pan, having an open bottom, a closed top and a foraminous side.

5. The combination with a radiator comprising a plurality of spaced sections, of an elongated pan supported upon the top of said radiator, said pan having a longitudinal

opening through its bottom, upon each side of the center line thereof, elongated vertical wicks passing through said openings and depending between the sections of the radiator inwardly of the outer edges thereof, means for supporting said wicks from the pan, and transverse wicks for feeding water to the vertical wicks, from the pan.

In testimony whereof he affixes his signature.

ROBERT A. CRAWFORD.
